UNITED STATES PATENT OFFICE.

PIUS L. SHEPLER, OF TOLEDO, OHIO, ASSIGNOR OF ONE-FIFTH TO CORYDON W. MUNSON, OF SAME PLACE.

DESIGN FOR A GUARD-FINGER FOR HARVESTERS.

SPECIFICATION forming part of Design No. 32,965, dated July 17, 1900.

Application filed June 19, 1900. Serial No. 20,904. Term of patent 14 years.

To all whom it may concern:

Be it known that I, PIUS L. SHEPLER, a citizen of the United States, residing at Toledo, in the county of Lucas and State of Ohio, have invented and produced a certain new and original Design for Guard-Fingers for Harvesters, of which the following is a specification, reference being had therein to the accompanying drawings, in which—

10 Figure 1 is a perspective view. Fig. 2 is a plan. Fig. 3 is a side elevation, and Fig. 4 is a cross-section on line $x\text{-}x$, Fig. 2.

The general form of the guard-finger is that of a spear-head or tapering point A, having 15 the barbs or points a upon opposite ends thereof. The central portion of the body is cut away to form a horizontal slot b , open at the rear and forming a tapering portion c above said slot, which is of lesser width in

cross-section than the tapering portion d below the slot. Extending rearward from the portion d is the laterally-enlarged shank e .

The leading feature of the design is the horizontally-slotted spear-shaped body or tapering point having barbs or points upon opposite sides thereof and the portion above the slot being of lesser width in cross-section than the portion below the same.

What I claim as my invention is—

The design for a guard-finger for harvesters, 30 substantially as shown and described.

In testimony whereof I affix my signature in presence of two witnesses.

PIUS L. SHEPLER.
